UNITED STATES PATENT OFFICE.

WALTER H. DEUBENER, OF ST. PAUL, MINNESOTA.

ENVELOPE.

Application filed March 19, 1920. Serial No. 367,129.

To all whom it may concern:

Be it known that I, WALTER H. DEUBENER, a citizen of the United States, residing at St. Paul, in the county of Ramsey and 5 State of Minnesota, have invented a new and useful Improvement in Envelopes, of which the following is a specification.

This invention relates to an envelope designed with a locking closure to obviate the 10 necessity of adhesive for sealing the same and to provide an envelope of simple, inexpensive design.

The closing and locking flap of the envelope is formed with a locking means 15 which engages in slots designed to receive the same, while suitable recesses form notch engagements for the locking means to hold the flap in locked closed position.

A further object of the invention is in 20 providing a tongue positioned between the locking means on the closing flap to form a key to prevent the locking means of the closing flap from unlocking until the key or tongue is released from a slot formed 25 back of the envelope when the closing flap is in locked closed position.

The closing flap is also provided with a finger engaging tongue formed in the body portion of the same which can be engaged 30 to unlock the closing flap without the necessity of tearing the envelope.

In the accompanying drawings forming part of the application:

Figure 1 is an elevation of the envelope 35 closed.

Figure 2 illustrates a portion of the envelope with the closing flap in open position.

Figure 3 illustrates a portion of the envelope, showing the closure flap in closed 40 position with a locking key tongue formed therewith.

The drawings illustrate the envelope A from the rear side of the same, which is 45 formed with flaps 10 and 11 and a short flap 12 along the bottom edge of the same projecting from the body or front portion 13 of the envelope. The flaps 10 and 11 in this construction of envelope constitute the 50 main portion of the back and fold over each other with a narrow margin along the longitudinal center of the envelope, the overlapping portions being pasted together while the flap 12 is folded over and pasted to the 55 flaps 10 and 11 to close one end of the envelope.

The open end of the envelope is closed by the closure flap 14, which is formed with locking tongues 15 on either side of the same, equally disposed from each other from the longitudinal center of the flap and envelope at the ends of the straight, transversely extending edge 16, which extends approximately parallel to the score line 17, upon which the flap 14 hinges. The locking tongues 15 have a circular outer shape and are provided with a deep recess or notch 18 on one side between the body of the flap and the tongue 15. Slots 19 are formed in the portions 10 and 11 to receive the tongues 15 and the slots are so positioned as to cause the recesses 18 of the tongues to be drawn toward and in close proximity to one end of the slots when the closing flap 14 is in locking position 75 after the tongues are inserted in the slots, as illustrated in Figure 1.

A finger engaging tongue 20 is formed in the body portion of the closure flap 14. This tongue 20 is cut in the body portion of the closure 14 and can be readily engaged by the fingers to withdraw the tongues 15 from their locking position to unlock the envelope without tearing the same. The tongue can also be engaged while inserting 85 the locking tongues 15 in position to lock the closure 14.

This construction of envelope securely locks the closure 14 against accidental opening and without the necessity of using adhesive on the closure tongue, or other expensive means, as compared to this construction, for locking the same. The envelope A is of simple, inexpensive construction, requiring no more material to manufacture than is used in the ordinary envelope of this design. It is obvious that the shape and design of the general body portion and flaps of the envelope can be varied 95 to suit the occasion and requirements.

The construction of the envelope B, illustrated in Figure 3, is practically the same as the envelope A, the locking tongue 14 being formed with the locking tongues 15, recesses 18 and the engaging tongue 20. The tongues 15 engage in suitable slots 19 formed in the back 10 of the envelope, but the flap 11' is shorter than the flap 11, illustrated in the envelope A, while the flap 10 forms practically the entire back of the envelope. In this construction the closing flap 14 is formed with a projecting tongue 110

or key 22, which engages in the transversely extending slot 23 formed in the back 10 of the envelope B. The tongue 22 projects from the transverse edge 16 and is centrally positioned between the locking tongues 15. The slot 23 is positioned in such relation to the slots 19 that when the tongues 15 are engaging in the slots 19 the tongue or key 22 is adapted to force and hold the recesses 18 into close engagement with one end of the slots 19 so that the body portions of the tongues 15 are locked against disengagement from the slots 19, until the locking key or tongue 22 is removed from the slot 23. Thus the envelope B is provided with a positively locked closure 14 to prevent easy opening of the envelope, whereas when it is desired the envelope can be readily opened by unlocking the tongues 15 from the slots 19 by withdrawing the key 22 from the slot 23.

The drawings illustrate the invention applied to the envelope in a particular manner but it is desired to have it understood that the invention can be varied and applied to uses other than those set forth without departing from the spirit of the invention.

What I claim is:

1. An envelope comprising a pair of members, a cover closure flap hinged to one of said members, a pair of circular locking tongues extending from the edges of one of said members, arcuate slots formed along the perimeter of portions of said locking tongues and slots formed in said other member adapted to cooperate with said locking tongues.

2. An envelope comprising a pair of members, a cover closure flap hinged to one of said members, said closure flap having an edge parallel to said hinge, circular locking tongues issuing from the edge of said closure flap having its perimeter tangential to said parallel edge, arcuate slots of uniform width extending partially around the perimeter of said circular tongues, said slots being so positioned as to form the neck of said tongue of a width less than the diameter thereof, and cooperating slots in said other member adapted to be engaged by said locking tongues, said slots being positioned so as to engage said arcuate slots in

the extreme ends thereof at the necks of said locking tongues to lock the flap in place upon the envelope. 55

3. An envelope comprising a pair of members, a cover closure flap hinged to one of said members, a pair of locking tongues positioned on the sides of said flap inwardly from the edges thereof and arcuate slots formed on said cover closure flap along the perimeters of said locking tongues, said closure flap being cut away at its corner on lines tangent with said arcuate slots and extending outwardly towards the hinge of 65 the cover closure flap.

4. An envelope of the class described, comprising a front body portion, side and end flaps, a cover closure flap having oblique edges, locking tongues projecting 70 from the oblique edges of the closure flap, slots formed in said side flaps for receiving said locking tongues, notches formed adjacent said tongues, the oblique edges of 75 said closure flap being adapted to engage in one end of said slots and a finger engaging tongue formed in the body of said cover closure flap for said envelope.

5. An envelope, including a body portion, overlapping flaps forming the back of said envelope, a cover closure flap, a pair of locking tongues extending from the edges of the cover flap, slots formed in the back of said envelope for receiving said pair of tongues, a key tongue formed at the apex 80 of said cover flap and extending outwardly beyond said locking tongues and a slot formed in said back adapted to receive said key tongue to hold said pair of locking tongues in locked position to close said 85 envelope.

6. An envelope formed with overlapping back flaps, a cover flap hinged to said envelope and adapted to overlap the back flaps when in closed position, a pair of slots formed in the back of said envelope extending parallel to each other, a slot formed in said back interposed between said parallel slots, locking tongues and a key tongue adapted to engage in said pair of slots and said interposed 100 slot, respectively, to lock said cover flap to close said envelope.

WALTER H. DEUBENER.
